Primary Examiner — Angela J Lee

(57) **CLAIM**

The ornamental design for a lanyard, as shown and described.

DESCRIPTION

FIG. 1 is a bottom-left perspective view of a lanyard showing my new design;

FIG. 2 is a top-right perspective view thereof;

FIG. 3 is a left side view thereof;

FIG. 4 is a top view thereof;

FIG. 5 is a front view thereof;

FIG. 6 is a back view thereof; and

FIG. 7 is a right side view thereof; and,

FIG. 8 is a bottom view thereof.

The broken lines showing the unclaimed features form no part of the claimed design.
